UNITED STATES PATENT OFFICE.

EDMOND E. KINSEY, OF SAN ANGELO, TEXAS.

PUMP JACK.

Application filed March 17, 1926. Serial No. 95,373.

The invention relates to pump operating mechanism and provides a jack including an endless member as means for imparting a reciprocatory movement to the pump rod.

5 While the drawings illustrate a preferred embodiment of the invention it is to be understood that in adapting the means to meet specific needs and requirements, the design may be varied and such other changes in the 10 minor details of construction may be resorted to within the scope of the invention as claimed, without departing from the spirit thereof.

15 For a full understanding of the invention and the merits thereof, reference is to be had to the following description and the drawings hereto attached, in which—

Figure 1 is a top plan view of a pump jack embodying the invention,

20 Figure 2 is a front view of the jack,

Figure 3 is a side view of the jack, the drive shaft being in section,

25 Figure 4 is a detail sectional view of a portion of the endless member and pump rod on the line 4—4 of Figure 2, and

Figure 5 is an enlarged sectional view on the line 5—5 of Figure 2.

30 Corresponding and like parts are referred to in the following description and designated in the several views of the drawings by like reference characters.

The jack comprises a head which includes a base 1 and spaced uprights 2.

35 Brackets 3 are provided at the upper ends of the upright 2 and shafts 4 are mounted in the upper ends of the brackets and uprights. The shafts 4 are in transverse alignment and each has a spur gear 5 and a sprocket wheel 6 fast thereto. The 40 spur gears 5 are disposed between the brackets 3 and uprights 2. The sprocket wheels 6 are located at the inner ends of the shafts. Other shafts 7 are mounted in the lower portion of the uprights in transverse alignment and are provided at their inner ends with sprocket wheels 8 which are fast thereto. A yoke 9 is provided with outwardly disposed bearings 10 in which the shafts 7 are mounted. The bearings 10 are received

50 in vertical slots 11 of the uprights 2 and are adjustable vertically and are held in the adjusted position by suitable means such as screws 12 which are threaded into the bearings 10 and pass through slots 13 formed in the uprights 2. Endless chains 14 pass around the sprocket wheels 6 and 8 and con-

stitute the endless member for operating the pump rod.

A pin 15 is supported at its ends in transversely aligned links of the endless chains 14 and the pump rod 16 is connected to the endless member by means of the pin 15. A coupling 17 is bolted or otherwise secured to the pump rod 16 and receives the pin 15 which passes through an opening formed 65 therein. It is observed that there is an unobstructed space between the endless chains 14 which provides clearance for the pump rod 16 which travels upwardly and downwardly and between the runs of said chains 70 when the jack is in operation. A drive shaft 18 mounted in bearings at the upper ends of the uprights 2 is provided with spur pinions 19 which are in mesh with the spur gears 5 and in this manner, both shafts 4 75 are uniformly rotated. The drive shaft 18 may be operated in any manner, either by hand or motor, and when driven from a suitable source of power, a drive belt, not shown, coacts with a drive pulley 20 fast to the 80 shaft 18. When the jack is in operation the elements 14 of the endless member are uniformly rotated, thereby causing the pin 15 to travel upwardly and downwardly and the pump rod 16 connected to said pin receives a corresponding reciprocatory movement, thereby resulting in operation of the 85 pump in a manner well understood.

Having thus described the invention, I 90 claim:

1. A pump jack comprising a head, including spaced uprights formed with longitudinal slots, a yoke having outwardly disposed bearings received in the slots of the uprights, shafts mounted in the bearings of the yoke and spaced apart at their inner ends, other shafts mounted in the upper ends of the said uprights and spaced apart at their inner ends, sprocket wheels upon the inner ends of the respective shafts, endless sprocket chains connecting the sprocket wheels of corresponding shafts, a pin connected at its ends with the sprocket chains, and a pump rod connected to the said pin. 95

2. A pump jack comprising a head, including a base, spaced uprights rising from the base and formed with intersecting longitudinal slots, and brackets at the upper ends of the uprights, transverse shafts mounted in the said brackets and uprights and spaced apart at their inner ends, spur gears fast to the shafts intermediate the brackets and 100

105

110

uprights, a drive shaft mounted in the uprights, pinions fast to the drive shaft exterior to the uprights and in mesh with the said spur gears, sprocket wheels fast to the inner ends of the transverse shafts, a yoke having outwardly disposed bearings received in slots of the uprights, means operating in slots of the uprights to secure the yoke in adjusted position, transverse alined spaced

shafts mounted in the bearings of the yoke, 10 sprocket wheels at the inner ends of the last mentioned shafts, sprocket chains trained about the sprocket wheels of corresponding shafts, a pin connected at its ends to the sprocket chains, and a pump rod connected 15 to the said pin.

In testimony whereof I affix my signature.
EDMOND E. KINSEY. [L.S.]
